US0D1041159S

(12) **United States Design Patent** (10) Patent No.: **US D1,041,159 S**
(45) Date of Patent: ** Sep. 10, 2024

(54) **BAG**

- (71) Applicant: **MCM GLOBAL AG**, Zug (CH)
- (72) Inventors: **Sungjoo Kim**, Seoul (KR); **Youngnan Jang**, Seoul (KR); **SooJung Seo**, Seoul (KR); **Sooyeon Lee**, Seoul (KR); **Jihyun Nam**, Seoul (KR); **Hey Min Park**, Seoul (KR); **Sanghee Lee**, Seoul (KR); **Sun Young Ahn**, Seoul (KR); **Sang Mi Lee**, Seoul (KR); **Eun Soo Choo**, Seoul (KR); **Jihye Lim**, Seoul (KR)
- (73) Assignee: **MCM GLOBAL AG**, Zug (CH)
- (**) Term: **15 Years**
- (21) Appl. No.: **29/859,555**
- (22) Filed: **Nov. 10, 2022**

Related U.S. Application Data

- (62) Division of application No. 35/511,923, filed on Nov. 26, 2020 (U.S. filing date under 35 U.S.C. 384), and having an international filing date of Nov. 26, 2020, now Pat. No. Des. 975,434.
